Application December 18, 1933, Serial No. 50,105

Term of patent 7 years

To all whom it may concern:

Be it known that I, AUGUSTUS M. REID, a citizen of the United States, whose post office address is 7 West 45th Street, New York city, in the county and State of New York, have invented a new, original, and ornamental Design for Bracelets, of which the following is a specification, reference being had to the accompanying drawing, forming part thereof, in which

The single figure of the drawing is a plan view of a bracelet composed of fur, in this representa-

tion a pair of ermine tails. The tails are strung upon cord or wire to hold them in shape, the ends of the wire being joined by a clasp. The clipped ends of the tails are each covered by a cap and a decorative bead or ornament is mounted between the tails. The bead or ornament may be varied in color.

I claim:

The ornament design for a bracelet, as shown and described.

AUGUSTUS M. REID.
